UNITED STATES PATENT OFFICE.

BENJAMIN BAYLISS, JR., OF BELTZHOOVER, PENNSYLVANIA.

APPARATUS FOR MANUFACTURING STEEL.

SPECIFICATION forming part of Letters Patent No. 361,256, dated April 19, 1887.

Application filed May 7, 1885. Serial No. 164,652. (No model.)

To all whom it may concern:

Be it known that I, BENJAMIN BAYLISS, Jr., of Beltzhoover, in the county of Allegheny and State of Pennsylvania, have invented certain new and useful Improvements in Apparatus for Manufacturing Steel; and I do hereby declare that the following is a full, clear, and exact description thereof, reference being had to the accompanying drawings, and to the letters of reference marked thereon, which form part of this specification.

My invention relates to apparatus for manufacturing iron and steel; and its objects are, first, to provide for easily maintaining a fluid-temperature of the mass during transit, and, second, to secure that end with simplicity of plant. I accomplish these aims by the means illustrated in the accompanying drawings, in which—

20 Figure 1 is an elevation of the converter and accessories embodying the principles of my invention. Fig. 2 is a vertical section of the converter. Fig. 3 is an elevation of the platform capable of vertical reciprocation and adapted to hold the truck and appurtenances shown. Fig. 4 is a view of the handle by which the efflux of slag is controlled. Fig. 5 is a vertical section through the platform of the truck and cogged turn-table, showing their 25 relative position. Fig. 5 shows a plan view of the truck. Fig. 6 is a detail view of the valve which regulates the discharge of the slag; and Fig. 7 is a detail view of the under side of the platform, showing the sliding ball-and-socket joints operating in slots, whereby 30 the vertical reciprocations are effected.

Similar designations indicate corresponding parts in all the views.

In practice it has been found that the use of 40 the bottom section of a converter, to serve as a movable receptacle for the molten mass to and from the stationary portion of the converter, (besides its normal function), involves a loss of heat and consequent fluidity, which 45 seriously impairs the successful execution of subsequent operations. This invention is therefore intended to supply a deficiency in the apparatus shown in Patent No. 313,079, granted to me March 3, 1885, to the end of 50 obviating the objection noted.

A B C represent the sections of my converter. Concentric with the section A is a

hot-air chamber, N', having removable covers O, to permit of renewing tuyeres Q. The section B is keyed and luted to section A, and they normally rest together upon supports F' 55 F''. The air-passage N is attached to the outer surface of section B, and connects the hot-blast pipe G with the chamber N'. The section B is also provided with trunnions P P, rotating 60 in bearings F F'' when so actuated by the gear-wheel K, operated by an endless screw, K'. On the other side, where the blast is admitted, a cold-water pipe, I, is provided to maintain 65 an even temperature with that of the other trunnion. The section C is intended to be removably joined to B by keys and luting, for it is a feature of my invention that this section shall, besides its normal purpose, serve as a ladle to transport the fluid mass from the furnace to the converter. A cog-wheel, S, on the 70 side of C, when operated by a pinion to which power is transmitted by a band-wheel, H, tends to alter the inclination of the support D and the contained section C to pour the metal. 75 The support D is secured upon the truck R³, which, by means of the movable platform E, can receive section C from and restore it to section B. The truck R³ is recessed at R⁵ to permit of placing the cogged turn-table R⁴ and 80 the operating-pinion R' flush with its surface. An annular groove, R⁶, is provided to accommodate the bolts R⁸ during rotation, and a 85 socket or depression, R', affords a bearing for the spindle R⁹, on which the turn-table revolves. The frame R², being bolted to the turn-table R⁴, moves synchronously therewith and transmits the imparted motion to the supports D, thus horizontally varying the position of the section C, so as to bring its spout 90 M in alignment with a suitable discharge-receptacle.

When the section C is in transit between the furnace and the stationary portion of the converter, a cover, C', is provided to keep approximately a uniform temperature therein. 95 A loop, X, serves to handle the same, and a hinged door, Y, permits inspection of the interior. Weighted levers L' L', attached by a sliding ball-and-socket joint to the base of the 100 platform E and secured rigidly to the shafts T T, effect the reciprocations of the platform, the movement of the levers in an arc of a circle being caused by a pinion, U, on the shaft

U', which derives its motion from gear-wheels T' T' on the shafts T T, that are actuated by a hand-wheel, V. M is an aperture, through which metal and slag are poured. W is a valve to control the efflux of slag from section C, and it is operated by a handle, W', which is rigidly secured thereto. X' X' are platform-guides.

The operation is as follows: The section C is run to the furnace by truck R'. The molten metal is then charged. The cover C' or its equivalent is then placed on the section. The truck and contents are conveyed to the stationary portion of the converter. The cover C' is removed. The section C is secured to section B by keys and luting, the hot blast turned on, and the converter alternately inverted and restored to secure homogeneity of the mass. The slag is drawn. The section C is disjoined and conveyed to the molds, where its contents are poured. Any remaining slag is dumped after the metal has been discharged.

I do not herein claim the process by which this apparatus is operated, as the same has been secured to me by Patent No. 347,913, granted on the 24th day of August, 1886.

Heretofore a sectional converter has been employed, whose lower portion could be conveyed to charge and discharge the metal, as shown in my patent of March 3, 1885, above referred to; but therein no provision was made for maintaining fluidity of the mass during transit.

I am also aware that a unitary converter has been patented, in which a semicircular plate is secured by bolts or clamps over the mouth of the same, as well to prevent the escape of gases from the mass as to obviate atmospheric access during transit of the converter. My invention is solely addressed, however, to the maintenance of a fluid-temperature in sectional converters during transit.

Having thus fully described my invention, what I claim, and desire to secure by Letters Patent of the United States, is—

The sections A, B, normally joined, the latter having central supporting trunnions, P P, one of which is hollow to admit an air-current, and the other having a gear-wheel, K, to cause vertical rotation, bearings F F' and supports F' F', in combination with the section C, provided with trunnions, the truck R', provided with a hand-wheel, R, the supports D, the platform E, and the means for raising and lowering the platform, as described, the whole co operating for the purpose set forth.

In testimony that I claim the foregoing as my own I affix my signature in presence of two witnesses.

BENJAMIN BAYLISS, JR.
